FILLING END SEPARATOR FOR MULTIPLE SHUTTLE LOOMS

Fred J. Leard, Westminster, S. C.

Application February 1, 1951, Serial No. 208,943

8 Claims. (Cl. 139—170.6)

1

This invention relates to multiple shuttle looms and more especially to an improved attachment for preventing idle filling yarns which extend from the adjacent selvage of the cloth being woven to a vertically reciprocable multiple compartment shuttle box from becoming entangled with each other or from being drawn into the fabric being woven by an outgoing shuttle.

As is well known to those familiar with the art, as a shuttle is thrown across the lay of a loom into one of the compartments of a vertically reciprocable multiple compartment shuttle box, there is disposed between the adjacent selvage and the multiple compartment shuttle box a portion of filling yarn. The shuttle box may then be elevated or lowered according to the desired pattern and a shuttle from another compartment will be thrown out of the multiple compartment shuttle box across the lay after which this shuttle will be thrown back across the lay to return to the same compartment. Now, as the second-named shuttle is thrown out of the corresponding compartment in the multiple compartment shuttle box, the portion of the yarn from the previously cast shuttle which extends between the selvage of the cloth of the fabric being woven and the shuttle box may be pulled back into the woven material or fabric or may become otherwise entangled with these previously cast portions of the filling yarn which may subsequently sever these portions of the yarn requiring that the loom be stopped, and in the event of the yarn being drawn into the fabric being woven, it results in defective fabric and a substantial loss.

It is therefore an object of this invention to overcome such defects as heretofore described by providing an individual automatic means operatively connected to the shuttle box for elevating each of the yarns as the shuttle in the corresponding compartment is elevated and to thereby permit any shuttles therebelow to be thrown across the lay without encountering the previously cast filling yarn or yarns.

It is another object of this invention to provide a simple and efficient means which operates independently of the usual operating mechanisms of a loom and which not only serves to elevate the yarn extending from a corresponding shuttle as the shuttle box is elevated, but to also clamp previously cast portions of the yarn which extend between the selvage of the cloth being woven and the shuttle box and which may be connected to shuttles disposed below the horizontal plane of the lay and to thereby, also, prevent the yarns extending from lowered compartments from being folded back into the shed.

2

More specifically, it is an object of this invention to provide a plurality of spring biased fingers which are pivotally mounted on a multiple compartment shuttle box, there being one of these fingers disposed adjacent the lower surface of each of the compartments and the uppermost of these fingers normally being biased upwardly while those fingers therebelow are normally biased downwardly and each of the fingers being provided with suitable stop means to limit their movement in the direction in which they are biased with the result that, as the shuttle box moves upwardly from the lowermost position, the uppermost finger will move upwardly therewith as the compartment therebelow is aligned with the upper surface of the lay and, upon a compartment below said second compartment subsequently being positioned in alignment with the race plate of the lay, the corresponding finger which has heretofore been biased into engagement with the upper surface of the lay or with a suitable notch provided in the lay for reception thereof, will move upwardly to substantially the same horizontal plane as the lower surface of the corresponding compartment to thus also elevate this yarn therewith so as not to be affected by the operation of the shuttle disposed therebelow. On the other hand as each of the shuttle boxes moves downwardly, the corresponding finger moves downwardly and engages the upper surface of the portion of filling yarn extending between the selvage and the corresponding one or more of the compartments disposed therebelow to thus clamp this filling yarn between the lower surface of the corresponding finger and the upper surface of the lay.

Some of the objects of the invention having been stated, other objects will appear as the description proceeds when taken in connection with the accompanying drawings in which—

40 Figure 1 is a perspective view showing a portion of a vertically reciprocable multiple compartment shuttle box on one end of a lay and showing the improved yarn separator means in association therewith;

45 Figure 2 is a top plan view of the structure shown in Figure 1;

Figure 3 is a vertical sectional view taken substantially along the line 3—3 in Figure 2 but omitting the shuttles from the corresponding compartments and also omitting the filling yarns;

50 Figure 4 is an elevation similar to Figure 1 but showing the filling yarn from the shuttle in the top compartment of the shuttle box extending to the selvage of the fabric being woven.

55 Referring more specifically to the drawings,

the numeral 10 indicates the conventional lay of a loom which is suitably secured to the upper portions of a pair of spaced swords 11, only one of which is shown in the drawings. Each of the swords 11 has a pitman pin 12 therein to which the front end of a pitman rod 13 is pivotally connected, the rear end of this pitman rod 13 being connected to the crank on a conventional crank shaft of the loom, not shown. Spaced above the lay 10 is a suitable reed cap 16 which is suitably secured to the corresponding swords 11 and disposed between the reed cap 16 and the lay 10 is a suitable reed 16a forwardly of which is disposed a conventional race plate 17 which is suitably secured to the upper surface of the lay.

It will be observed in Figures 1, 2 and 4 that the race plate is cut away to provide a notch or cavity 19 therein, the bottom of which, in this instance, is defined by the upper surface of the lay 10 although it is to be understood that the cavity 19 need only be of such depth as to accommodate the forwardly and rearwardly extending portions of the separator fingers or wires to be later described.

The end of the lay shown in the drawings is provided with the usual lay end casting 18 and in which one end of a conventional protection rod 21 is oscillatably mounted. This protection rod 21 has a conventional pressure arm 22 fixed thereon and extending upwardly therefrom and which is adapted to engage the free ends of a plurality of binders 23 which extend outwardly and are pivoted by conventional means, not shown, and are pressed inwardly at their free ends to properly box the corresponding shuttles by conventional springs indicated at 24 in Figure 3. These binders 23 are parts of a conventional vertically reciprocable multiple compartment shuttle box comprising side plates 26 and 27 and having a plurality of horizontal partitions 28, 29, 30 and 31 and a bottom 32 which define four shuttle receiving compartments A, B, C and D.

The reed cap 16 is provided with a conventional shuttle guard 35 which extends from one end thereof to the other and which constitutes no part of the present invention. The upper end of the pressure arm 22 is biased rearwardly or towards the shuttle box by conventional spring means, not shown, associated with the protection rod 21, and in order to limit outward movement of the binders 23, there is provided a combined stop and support member indicated at 42 which is suitably secured, as by welding, to the front box plate 26 by legs 43 and 44. This combined stop and support member 42 has a plurality of horizontal portions 45 for assisting in guiding the free ends of the binders 23. The parts heretofore described are the usual parts of a multiple shuttle loom and it is with these parts that the present invention is adapted to be associated.

It will be observed in Figures 1 and 4 that a suitable bracket or plate 50 is suitably secured, as by bolts 51, to the front surface of the front plate 26 and adjacent the end of the shuttle box nearest the selvage of the cloth fabric being woven. The bracket 50 is threadably penetrated by a plurality of vertically spaced bolts, three of which are shown in the drawings and which are indicated at 54, 55 and 56. Suitable lock nuts 57 are provided on the inner ends of these bolts.

Collars 60, 61 and 62 are oscillatably mounted

on the respective bolts 54, 55 and 56 and it will be noted that these collars are eccentrically mounted on the corresponding bolts 54, 55 and 56 so as to provide portions thereon which are penetrated by respective separator fingers 65, 66 and 67, these fingers 65, 66 and 67 being suitably secured in the corresponding collars 60, 61 and 62.

It will be noted that each of these fingers extends inwardly towards the center of the lay and it curves upwardly and then downwardly and these fingers 65, 66 and 67 are provided with rearwardly extending portions 65a, 66a and 67a, respectively, which are adapted to, at times, rest in the cavity 19 in the race plate 17. It might be stated that each of the fingers 65, 66 and 67 is curved in the manner described between its respective collar and the corresponding rearwardly extending portions 65a, 66a and 67a so as to provide a generally upwardly curving portion which extends slightly above the upper surface of the race plate 17 when they are in a lowered position and also extends upwardly when they are in a raised position to thus retain the filling thereon during rearward movement of the lay.

Since the rearwardly extending portion 65a of the uppermost finger 65 would never have occasion to move upwardly beyond the horizontal plane of the bottom 29 of the upper compartment A as the shuttle box is moved to a lowermost position, the upper separator finger 65 is biased upwardly by a suitable torsion spring 70, one end of which encircles the portion of the upper separator finger 65 adjacent the collar 60 and the other end of which is disposed in one of a pair of transverse slots 72 in the head 73 of the bolt 54, the medial portion of the torsion spring 70, of course, encircles the bolt 54. It will be observed in Figures 2 and 4 that a portion of the separator finger 65 projects through the collar 60, to the left in Figure 4 and normally engages a suitable stop pin 75 secured in the plate or bracket 50 and which is provided to limit upper movement of the free end of the separator finger 65 so that the forwardly and rearwardly extending portion 65a thereof is normally disposed at substantially the same horizontal plane as the bottom 29 of the upper compartment A.

It might be stated that the uppermost separator finger 65 is normally biased upwardly so that, as the shuttle box is moved upwardly to its uppermost position, the rearwardly extending portion 65a thereof may engage the lower surface of the reed cap to thus cause the finger 65 to move in a clockwise direction in Figures 1 and 4 and will thus not interfere with upward movement of the shuttle box. However, if the reed cap 16 does not extend outwardly to where it will extend above the vertical plane of the rearwardly extending portion 65a of the upper separator finger 65, then the upper separator finger 65 would not have to be biased in either direction and could remain in fixed relation to the bottom 29 of the upper compartment A.

The collars 60, 61 and 62, which are oscillatably and eccentrically mounted on the bolts 54, 55 and 56 have the respective fingers 66 and 67 projecting therethrough in off center relation. These fingers are normally biased downwardly to cause the outer ends of these separator fingers 66 and 67 to normally engage respective stop pins 83 and 86 suitably secured in the bracket 50. The separator fingers 66 and 67 are normally biased down-

wardly at their free inner ends by respective torsion springs 80 and 87 which encircle the respective bolts 55 and 56.

One end of the torsion spring 80 is bent around the finger 66 adjacent the collar 61 and the other end thereof is disposed in one of a pair of transverse slots 81 in the head 82 of the bolt 55. One end of the torsion spring 87 is secured around the finger 67 adjacent the collar 62 and the other end thereof is disposed in one of a pair of transverse slots 89 in the head 90 of the bolt 56.

It is thus seen that the two fingers 66 and 67, are biased to cause their free ends to move downwardly but are limited as to downward movement by the respective stop pins 83 and 86, these stop pins 83 and 86 being so positioned that the rearwardly extending portions 66a and 67a of the respective separator fingers 66 and 67 will be disposed in substantially the same horizontal plane as the bottoms 30 and 31 of the respective compartments B and C in the shuttle box when these particular compartments are elevated above the horizontal plane of the race plate 17. On the other hand, as the compartments other than the uppermost compartment A are lowered below the horizontal plane of the race plate 17, the lower surfaces of the rearwardly extending portions 66a and 67a of the respective fingers 66 and 67 will engage the upper surfaces of the yarns extending from the shuttle box disposed therebelow to the selvage of the fabric being woven to thus clamp this yarn against the upper surface of the lay in the notch 19 so that the yarn will not be drawn into the shed.

In the drawings, there are shown filling yarns F-1 and F-2 extending from the respective compartments A and B of the shuttle box to the selvage of the fabric being woven, although it is to be understood that similar filling ends would also extend from the compartments C and D, and, when the shuttle box is in the position shown in Figures 1 and 4, the filling end extending from both these compartments would be clamped beneath the rearwardly extending portions 66a and 67a of the fingers 66 and 67, respectively, while the filling end extending from compartment B is disposed above the rearwardly extending portions 66a and 67a of the separator fingers 66 and 67, respectively.

It is evident that upon downward movement of the shuttle box from the position shown in Figures 1 and 4, the lower surface of the rearwardly extending portion 65a of the separator finger 65 would assume a position between the two rearwardly extending portions 66a and 67a and would clamp the end extending from compartment B against the upper surface of the lay in the notch 19 as the shuttle from the compartment A is subsequently thrown across the lay above the rearwardly extending portion 65a of the separator finger 65. Since the finger 65a cannot move upwardly beyond the point at which it engages the corresponding stop pin 75 it is evident that the horizontal portion 65a thereof should be accurately adjusted or positioned so as to reside in the cavity 19 when the shuttle box is in a lowermost position, that is, when the compartment A is disposed in alignment with the race plate 17.

It is thus seen that the rearwardly extending portion 65a of the separator finger 65 will elevate the corresponding filling F-1 so as to hold the filling F-1 from the top compartment A in elevated position while the filling F-2 from another shuttle is projected from the compartment B to and fro across the lay to return to the com-

partment B. Thus, the filling F-1 will be elevated out of the path of travel of the shuttle carrying the filling F-2. Now, when the shuttle box is raised to the point where a shuttle is to be carried from and returned to the shuttle receiving compartment C, it is evident that the finger 66 will move a partial revolution in a clockwise direction in Figure 4 until it engages the stop pin 83 and will thus move upwardly with the shuttle box to elevate the filling F-2 to thereby move the same above the path of the shuttle to be discharged from the shuttle compartment C. Now, at this point, the rearwardly extending portion 65a will engage the lower surface of the reed cap 16. At this time, the transverse or rearwardly extending portion 66a of the separator finger 66 will also occupy a position substantially the same as that in which the separator finger 65 is shown in Figure 4.

Now, presuming that the shuttle box is elevated to its highest position to cause the shuttle receiving compartment D to be on the same level as the race plate 17, this would cause the finger 65 to be depressed by the lower edge of the reed cap and the finger 66 would be elevated against the reed cap while the finger 67 would also rise upwardly to lift the filling extending from the shuttle in compartment C since the finger would come in contact with the stop pin 86. All of the filling yarns from the shuttles in compartments A, B and C would thus be lifted above the lay and out of the path of travel of the shuttle from the compartment D.

For sake of clarity, in the drawings the filling yarns extending from the compartments C and D are omitted.

All of these operations are automatic as a result of the relative movement between the shuttle box and the lay of the loom and depend upon no pattern control means or other control apart from the loom as their only control is their corresponding torsion springs and the stop pins associated therewith which cause them to automatically assume the proper position depending upon which compartment of the shuttle box is being employed in the same horizontal level as the race plate 17 on the lay 10.

It is evident that the filling yarns extending from any of the compartments which may be disposed below the level of the lay will be clamped against the lay by the fingers of the compartment or compartments thereabove to also prevent these yarns from interfering with the operation of an active shuttle and to prevent the filling from the inactive shuttles from being pulled into the shed by the active shuttles.

It is thus seen that I have provided an improved filling separator for multiple shuttle looms that is simple and economical to manufacture, that employs but a minimum of parts, that does not interfere with existing parts of the loom and does not need to be coupled to any moving parts of the loom for operation thereby. The separator fingers of the device are so mounted as to be readily adapted to any type of loom. The curved portions of the fingers prevent the filling from slipping off the fingers during rearward motion of the lay and the stops on the bracket 50 insure positive positioning of the rearwardly extending portions of the corresponding fingers at each boxed position.

In the drawings and specification there has been set forth a preferred embodiment of the invention and although specific terms are em-

ployed, they are used in a generic and descriptive sense only and not for purposes of limitation, the scope of the invention being defined in the claims.

I claim:

1. In a multiple shuttle loom having a lay and also having a multiple compartment shuttle box vertically reciprocable up and down to a plurality of positions to bring a selected respective compartment opposite an end of said lay, an improved filling yarn separator for separating the portions of the filling yarns which extend from the adjacent selvage of the cloth being woven to the respective compartments of the shuttle box comprising at least two fingers oscillatably mounted on the shuttle box and having transverse portions on the free ends thereof which are normally disposed in engagement with the upper surface of the lay when the shuttle box is in a lowered position to cause the filling yarn cast into the corresponding compartment of the shuttle box to extend above the corresponding transverse portions, spring means associated with the uppermost of said fingers to urge the end thereof upwardly, stop means for restricting the upward movement of said uppermost finger, spring means normally urging the fingers other than the uppermost finger downwardly at their free ends and stop means associated with the corresponding last-named fingers for restricting downward movement of the free ends of said fingers to thus cause the fingers to move with the shuttle box upon further upward movement thereof and to remain in substantial alignment with the horizontal plane of the bottoms of the corresponding compartments in the shuttle box to thus elevate the filling yarns directed to the corresponding compartments upon upward movement of the shuttle box.

2. In a multiple shuttle loom having an oscillatable lay for weaving fabric and also having a reed cap spaced above the lay and being oscillatable therewith, said loom also having a vertically reciprocable shuttle box on at least one end of said lay provided with at least two compartments for accommodating corresponding shuttles, an improved filling yarn separator for elevating the filling yarn extending from the uppermost of the compartments to the adjacent selvage of the fabric upon a shuttle being thrown into said uppermost compartment and following the alignment of a lowermost compartment with the upper surface of the lay comprising a finger carried by the shuttle box and having a transverse portion on the free end thereof adapted to move up and down with up and down movement of the shuttle box, stop means on the shuttle box, spring means associated with the finger to normally urge the free end of the finger upwardly and said stop means being so positioned as to prevent the free end of said finger from moving to a position above the horizontal plane of the bottom of the uppermost compartment whereby, upon elevating the shuttle box, the finger may engage and be biased downwardly by the reed cap with the filling from the shuttle in the uppermost compartment held between the finger and the lower surface of the reed cap.

3. In a multiple shuttle loom having an oscillatable lay and also having a vertically reciprocable shuttle box on at least one end of the lay provided with top, middle and lower compartments for carrying respective shuttles

from which filling ends extend to the adjacent selvage of the fabric being woven, said loom also having a reed cap spaced above the lay, an improved filling end separator for separating said

5 filling ends adjacent the shuttle box comprising a top finger oscillatably mounted on a horizontal axis on the shuttle box and having a transverse portion extending from the free end thereof which normally rests on the upper surface of the lay when the top compartment of the shuttle box is in alignment with the top surface of the lay, spring means normally urging the free end of said top finger upwardly, stop means for restricting movement of the top finger, a middle finger oscillatably mounted on a horizontal axis on the shuttle box below said top fingers and also having a transverse portion thereon extending across the lay, spring means normally urging the free end of the middle finger downwardly to bring the transverse portion thereof into engagement with the upper surface of the lay when the top or middle compartment of the shuttle box is in alignment with the lay, stop means associated with the middle finger for restricting downward movement of the free end thereof whereby, upon upward movement of the shuttle box to align the middle compartment with the upper surface of the lay, the top finger will elevate the yarn extending from the top compartment to the selvage of the fabric so as to be out of the path of travel of the shuttle from the middle compartment and whereby, upon further upward movement of the shuttle box to align the bottom compartment with the upper surface of the lay, the upper finger will engage and be biased downwardly by the reed cap and the middle finger will elevate the yarn extending from the middle compartment to the selvage of the fabric so as to be out of the path of travel of the shuttle from the bottom compartment.

4. In a multiple shuttle loom having an oscillatable lay and also having a vertically reciprocable shuttle box at least one end of the lay provided with a plurality of compartments into which shuttles are adapted to be thrown from the opposite end of said lay, means for separating the filling ends which occur between the adjacent selvage of the fabric and the corresponding compartments of the shuttle box comprising an upper finger fixed on the shuttle box and having a transverse portion on its free end disposed in substantially the same horizontal plane as the uppermost compartment and across which the filling end from the uppermost compartment extends, a corresponding finger for which each of the compartments disposed beneath the uppermost compartment, each of the last-named fingers having a transverse portion on the free end thereof above which the filling end from the adjacent compartment of the shuttle box is adapted to extend from the adjacent selvage of the fabric being woven, spring means normally urging the free ends of the last-named transverse portions at the free ends of the last-named fingers downwardly into engagement with the upper surface of the lay, stop means projecting from the shuttle box and associated with each of the last-named fingers to restrict downward movement of the transverse portions thereof, said stop means being so positioned that, upon further upward movement of the shuttle box, the transverse portions of the corresponding last-named fingers will occupy a position substantially in the same horizontal plane as that of the lower

surfaces of the corresponding compartments to thus elevate the filling ends from the corresponding compartments therewith as they are moved above the horizontal plane of the lay to prevent entanglement of the filling ends which extend from the elevated compartments with the filling extending from any compartment which may be disposed in alinement with the lay.

5. In a multiple shuttle loom having an oscillatable lay and also having a vertically reciprocal shuttle box provided with a top compartment, one or more intermediate compartments and a lower compartment adapted to be selectively positioned in alinement with the upper surface of the lay, said loom also having a reed cap spaced above the lay and adapted to oscillate therewith, filling separator means for separating the filling ends which occur between the shuttle box and the adjacent selvage of the fabric being woven as shuttles are thrown into the corresponding compartments comprising a plurality of fingers mounted on horizontal axes on the front of said shuttle box, each of said fingers having a transverse portion on the free end thereof above which the filling ends from the corresponding compartments of the shuttle box to the selvage of the fabric being woven extend, there being a first one of these fingers associated with each of the intermediate compartments of the shuttle box, a second one of said fingers being associated with the top compartment, stop means extending from the shuttle box associated with each of said fingers, a first spring means associated with the second finger normally urging the transverse end thereof upwardly, said stop means preventing movement of the free end thereof above the plane of the lower surface of the top compartment, a second spring means associated with each of the first fingers corresponding to the intermediate compartments and normally urging the last-named fingers downwardly at their free ends, said stop means serving to cause the transverse portion of the corresponding last-named fingers to occupy a position in substantially the same horizontal plane as the bottoms of the corresponding compartments of the shuttle box upon the shuttle box being elevated, said first spring means associated with the second finger serving to permit the free end of the second finger to move downwardly with upward movement of the shuttle box as the transverse portion of the second finger engages the lower surface of the reed cap whereby, upon each of the top, intermediate and lower compartments being alined with the lay, the filling ends extending from the compartments thereabove will be elevated by the corresponding fingers to thus prevent entanglement of the filling ends from the elevated compartments with the filling from the selected compartment disposed in alinement with the lay.

6. In a multiple shuttle loom provided with a vertically reciprocal shuttle box structure having a plurality of shuttle receiving compartments

therein, a filling yarn separator comprising a bracket secured to said structure, a plurality of fingers pivotally mounted on said bracket, said fingers extending from said bracket inwardly of the loom and terminating in transverse yarn engaging portions, each of said fingers being associated with one of said compartments, means biasing the topmost of said fingers upwardly, fixed means preventing such upward movement substantially above the level of the floor of the top compartment, means biasing the remainder of said fingers downwardly and fixed means preventing such downward movement substantially below the level of the floors of their respective compartments.

7. In a multiple shuttle loom provided with a vertically reciprocal shuttle box structure having a plurality of shuttle receiving compartments therein, a filling yarn separator comprising a plurality of fingers pivotally mounted on said structure, said fingers extending from said structure inwardly of the loom and terminating in transverse yarn engaging portions, each of said fingers being associated with one of said compartments, means biasing the topmost of said fingers upwardly, fixed means preventing such upward movement substantially above the level of the floor of the top compartment, means biasing the remainder of said fingers downwardly and fixed means preventing such downward movement substantially below the level of the floors of their respective compartments.

8. In an attachment for multiple shuttle looms having the usual lay and a shuttle box structure provided with a plurality of shuttle boxes adapted to be shifted to bring the shuttles selectively into action, a plurality of yarn engaging fingers pivotally mounted on said shuttle box structure in substantial vertical spaced alignment, each of said fingers being associated with one of said shuttle boxes, means resiliently holding each of said fingers in substantially the plane of the floor of its corresponding box, fixed means restraining the uppermost of said fingers against pivotal movement above the plane of the top box floor and fixed means restraining the remainder of said fingers against pivotal movement below the plane of the floor of the boxes associated therewith.
